HYDRAULIC LIFT TRUCK

Herbert E. Page, Pasadena, Calif.

Application July 23, 1943, Serial No. 495,941

4 Claims. (Cl. 254—10)

This invention has to do with hydraulic lift trucks. While such trucks are, of course, known in the art and have advantages over mechanically actuated lift trucks in that the lifting mechanism may be actuated by shorter swings of the operating handle and thus may be better used where the space is relatively limited, a difficulty with presently known hydraulic lift trucks has been their slowness in operation, particularly in making initial contact of the elevator with the work to be lifted. Many manufacturers have endeavored to overcome this difficulty by making the trucks of a height to leave as little clearance as possible between the elevator and the work to be lifted. This practice, however, limits the use of such trucks to the lifting of loads elevated to the heights to which the trucks are specially adapted, and other difficulties have been encountered such as unevenness in the floor or obstructions preventing easy movement of the truck into position under the load where the clearance is limited.

It is, therefore, among the principal objects of my invention to provide a hydraulic lift truck which may be made of minimum height such as to provide ample initial clearance between the truck and work to be lifted, to permit easily rolling the truck under the load, and which at the same time embodies means for establishing quick contact of the elevator with the work to be lifted by using a minimum of manual pumping effort.

Another object is to provide a novel and efficient means for hydraulically operating the lift mechanism.

Another shortcoming of lift trucks has been their lack of braking mechanism to retard their movement along declining runways and the like after being burdened with a load. It is often necessary in moving a load from one point to another to move the lift truck along such declining runways and in such instances the practice has been for the operator to call for manual assistance to maintain control.

It is, therefore, a further object of my invention to provide a hydraulic lift truck incorporating a braking mechanism, and particularly a hydraulic mechanism actuated by the fluid pressure which maintains the load in elevated position, so that the braking pressure is governed in accordance with the load.

Still further advantages are provided by my invention and how those as well as the objects hereinabove pointed out are achieved will be best understood from the following explanation of one adaptation of the invention, for which purpose

I shall refer to the accompanying drawings, in which:

Fig. 1 is a side elevation, partly in section;

Fig. 2 is a plan view;

5 Fig. 3 is an enlarged section of the hydraulic unit;

Fig. 4 is a section taken on line 4—4 of Fig. 3;

Fig. 5 is a section taken on line 5—5 of Fig. 4;

10 Fig. 6 is an enlarged fragmentary section showing the brake valve unit; and

Fig. 7 is an enlarged elevation taken on line 7—7 of Fig. 2.

With particular reference to the adaptation shown in the drawings, I show a chassis or base having side frame members 5 and cross members 6, 6a.

20 Cross member 6a is somewhat U-shaped (Fig. 7) and has journalled therein a vertical spindle 7 having a bifurcated lower end 8. An axle 9 is disposed transversely of the lower end 8 and has wheels 10 rotatably mounted thereon. A cap 12 is secured atop spindle 7, as by bolt 14, the cap presenting bifurcations 15 between which is pivoted the operating lever to be described. A rear axle 30 is mounted at its ends in side members 5 and carries wheels 32.

25 The elevator platform has side members 40, an end member 41 and cross members 43, 43a, the platform being pivoted to swing relative to the chassis by means of links 45, 45a, 45b. The lower ends of links 45a are formed integral with a sleeve 44 which is rotatably mounted on axle 30, links 45b being rotatably mounted at their lower ends on the shaft 30. The upper ends of

30 the links 45a, 45b are rotatably secured to a spindle 47, which spindle is secured at its ends in the platform side frame members 40, spacer sleeves 46 being interposed between the outer ends of links 45a, 45b. It will be observed, therefore, that the elevator is raised from the lowered position shown in Figs. 1 and 2 by means of rotating the sleeve 44, the hydraulic mechanism for which will now be described.

35 The hydraulic unit comprises a body 50 having a cylinder or piston chamber 51 within which a work piston 55 is slidably mounted. Piston 55 has a rod 56 which is pivotally secured by bracket members 57 to the chassis side members 6, so that the piston at all times is held against 40 longitudinal movement relative to the chassis while the body 50 moves longitudinally relative to the piston and chassis.

45 The outer end of cylinder 51 is internally threaded and has threadedly mounted therein a block 60 which presents a longitudinal cylinder

bore 61 within which a pumping piston 64 is reciprocally mounted. The outer end of block 60 presents bifurcations or extensions 66 whose outer ends are pivotally secured to an arm 70, the lower end of the arm 70 being cast integral with the sleeve 44 so that arm 70 in conjunction with the sleeve and links 45a constitute a bell crank. Thus longitudinal movement of the body 50 causes rotation of the sleeve 44 and consequent swinging of the links 45a to raise the elevator platform.

Bifurcations 66 are longitudinally slotted at 66a to slidably receive a slide bar 73 which is secured to the outer end of piston 64. The opposite ends of bar 73 are pivotally secured to the respective actuating links 75.

A manual operating handle 80 has its lower end socketed in an operating lever 82 pivoted at 83 to the bifurcated cap 12, a roller 84 being journaled in the bifurcated lower end of the lever. A bell crank 90a is pivotally mounted by pin 91 to a supporting bracket 93, the latter bracket having two arms 93a secured to the side frame members 5 and two arms 93b secured to the cross member 6. One arm of the bell crank is pivotally connected to a link 75a which in turn is secured at its opposite end to links 75. The other arm of the bell crank has a plane bottom surface to be engaged by the roller 84 of the operating lever so that manipulation of the handle 80 operates the lever and bell crank to cause reciprocation of piston 64. A compression spring 94 interposed between slide bar 73 and the block 60 urges the piston 64 outwardly of cylinder 61.

A hydraulic fluid reservoir is provided in body 50 and consists of that portion of chamber 51 ahead or to the right of piston 55 and the auxiliary chamber 90, a passageway 91 being provided through the wall separating auxiliary chamber 90 from chamber 51. A filling plug 83 is threadedly mounted in a hole in the body communicating with the chamber 51.

Within the forward or left-hand end of the body I provide two transverse bores 95 and 96 (Figs. 3 and 4). Within bore 95 I threadedly mount a valve housing 100 having a longitudinal bore 101. A transverse passageway 103 and a tube 104 provide communication between bore 101 and cylinder 61, and a passageway 106 provides communication between bore 101 and chamber portion 51a behind piston 55. A poppet valve 110 seats towards the reservoir or inlet end of bore 101, being normally maintained in seated position by gravity although spring means may be utilized, if desired, said poppet valve having oppositely disposed stems 110a, 110b. A ball valve 115 in bore 101 seats towards poppet 110, being normally held against its seat by a coil spring 116. This spring 116 is of a strength sufficient to maintain ball 115 seated against pressure in cylinder 61 during preliminary operation of piston 64 or until the elevator platform contacts the work to be lifted. An inlet chamber 117 communicates with the reservoir and with the bore 101 through ports 118 provided in the inner end of the valve housing.

With the elevator in the lowered position shown in the drawings, actuation of the handle 80, together with pressure of spring 94, reciprocates piston 64. On each suction stroke poppet 110 is unseated and fluid is drawn from the reservoir into cylinder 61. Spring 116 being of a strength to maintain ball valve 115 seated until the elevator contacts the load to be lifted, each of the preliminary pressure strokes of piston 64 thus

moves the body 50 to the left, causing arm 70 to rotate sleeve 44 and swing the links 45a to raise the elevator into contact with the work. During this work-contacting operation the movement of the body to the left relative to the stationary work piston 55 creates a vacuum in chamber 51a behind piston 55 which draws fluid into that chamber from the reservoir through passageway 106 and past the poppet valve 121 reciprocally mounted in a housing 122, valve 121 being normally maintained in seated position towards the reservoir by coil spring 124. Reference will be made hereinafter to the specific construction of poppet 121.

After the elevator contacts the load to be lifted, further movement of the platform is caused by pressure in cylinder 61 generated by continued reciprocation of the pumping piston 64. That is, the contact of the elevator with the load affords sufficient resistance to further movement of the platform to cause ball valve 115 to be unseated on each pressure stroke of piston 64, each pressure stroke forcing fluid from cylinder 61, through tube 104, past ball valve 115 and through passageway 106 into chamber 51a. This operation causes the body 50 to move further to the left relative to the piston 55 and thus causes further lifting movement of the elevator.

When it is desired to lower the elevator, an eccentric cam 130 rotatably mounted in a longitudinal bore 131 in the body is rotated to first contact and press inwardly the valve stem 110a to unseat poppet 110 and release pressure from cylinder 61. Further rotation of the cam causes stem 110b, which is normally spaced from the ball valve 115, to move into contact with and unseat ball 115 to release the pressure from cylinder 51, the elevator then moving into lowered position by virtue of its weight, or its own weight plus the carried weight. A compression spring 111 is disposed in chamber 51 between piston 55 and plug 60 to return the elevator to lowered position if its weight or load should be insufficient.

The mechanism for operating the cam 130 includes the shaft 133 upon which the cam is secured, which shaft is rotated from a foot pedal 135a provided by one leg of a bell crank 135, a second bell crank 137, a radial arm 138 secured on shaft 133, and connecting links 139, 140. A coil spring 136 urges the bell crank 135 against the stop 138a carried by frame member 5. Packing rings 141 are provided at opposite ends of the cam.

Referring now more particularly to the poppet valve 121, it is mounted in the longitudinal bore of housing 122. Valve 121 has a longitudinal bore 150 which communicates with an inner chamber 151 within which chamber an auxiliary poppet 153 is reciprocally mounted. To provide a seat for the latter poppet, a plug 154 is secured in the inner end of bore 150, as by peening 150a, and this plug has a port 155 against whose inner peripheral portion poppet 151 seats, the poppet being urged against its seat by a spring 156. Port 155 communicates with the chamber 151 through a port 157 in poppet 153 and thus the latter poppet 151 functions as a safety relief valve in the event pressure in cylinder 51 becomes too great.

In the movement of lift trucks from one place to another, particularly while heavily loaded, when any declining runway is traversed, the truck is apt to run away unless some braking or restraining power is applied. I have, therefore, incorporated in my lift truck a hydraulic

brake which is actuated from the pressure side of the work piston 58 so that the braking pressure applied is proportioned to the load.

This braking mechanism includes a brake drum 160 having an expanding brake band 161 which is expanded into braking position by any suitable hydraulic mechanism, such as plungers 162 actuated by fluid pressure applied through tube 165, there being a spring 163 normally urging the band contracted.

A valve housing 167 is secured to one of the side frame members, this housing having a longitudinal bore providing a fluid chamber 168 in which a piston 170 having two heads 170a, 170b is reciprocally mounted. A pair of ports 171, 172 are provided through the side wall of the housing, port 171 communicating with the said tube 165 and port 172 communicating with the reservoir in the body 50 through tube 173. A bell crank 175 is pivotally secured on a side frame member 5 and has one of its arms operatively connected to the piston by means of connecting rod 176. The bell crank is operated to actuate the piston by means of a Bowden wire 177 connecting at one end to the bell crank 175 and connecting at its other end to a conventional operating lever, not shown, mounted on the handle 30. A tube 186 establishes communication between body chamber 51a and the bore of valve housing 167 through port 182. A coil spring 185 secured to frame member 5 and crank 175 urges the crank into the inoperative position shown in the drawings.

With the parts in the position shown in Fig. 6 the brake is inoperative. To brake the truck, the Bowden wire 177 is operated to move piston 170 downwardly in its cylinder until piston portion 170a uncovers port 182 and piston portion 170b covers port 172. Thus the brake-operating plunger 162 is subjected to fluid pressure on the pressure side of piston 58, which is determined by the load on the elevator. If the fluid pressure in chamber 51a should be insufficient, it may be augmented by operating the pumping piston 64 to increase the pressure in chamber 51a.

While, in the foregoing, I have resorted to considerable detail of structure and association of parts in describing a particular example of my invention, I wish it to be understood that I have done so merely to make my invention understood and that I do not limit my invention to such details. On the contrary, my invention is only to be limited as appears in the appended claims.

I claim:

1. In a hydraulic lift device having a base and a work-supporting member movably mounted thereon, operating means comprising a body having a bore therein providing a piston chamber and a fluid reservoir, a work piston reciprocally mounted in the piston chamber and separating the reservoir from the remainder of said chamber, a plug secured in and closing one end of the bore, a cylinder bore longitudinally in the plug coaxial with the body bore, a pumping piston reciprocally mounted in said cylinder bore and operable independently of the work piston to move the work-supporting member into contact with the work and operable thereafter to exert sufficient pressure in the piston chamber to cause further movement of the work-supporting member.

2. In a hydraulic lift device having a base and a work-supporting member movably mounted thereon, operating means comprising a body

movable relative to the base and operatively secured to the work-engaging member, said body presenting a longitudinal bore, a work piston slidably mounted in one end of the bore and separating it into a pressure chamber and a fluid reservoir, a rod extending from one end of the body and securing the work piston to the base, a block threadedly mounted in the other end of the bore, said block presenting a cylinder bore coaxial with the body bore, a pumping piston reciprocally mounted in the last-named bore, means providing a fluid passageway between the last-named bore and the pressure chamber, a check valve in said passageway seating towards the said last-named bore, means providing a fluid passageway between the last-named bore and the reservoir and a check valve in the last-named passageway.

3. In a hydraulic lift truck, the combination of a chassis, a work-supporting platform, a spindle mounted transversely of the chassis, a sleeve rotatably mounted on the spindle, link means secured to the sleeve and to the platform whereby upon rotation of the sleeve the platform is moved about a radius relative to the chassis, a radial arm secured on the sleeve, a body having a pair of spaced parallel longitudinally slotted extensions pivotally secured to the arm, said body being movable longitudinally relative to the chassis, a pair of longitudinal, oppositely disposed, piston chambers in the body, a work piston secured to the base and slidably mounted in the first of the chambers, a pumping piston reciprocally mounted in the second chamber and having a rod disposed between said extensions, a cross pin extending through the rod and being slidable in said slots, an operating lever pivotally mounted on the base, link means operatively connecting the lever to the cross pin, said body presenting a fluid reservoir, means providing a fluid passageway between the reservoir and the second chamber, a check valve in the passageway seating towards the reservoir, means providing a second fluid passageway between the first and second chambers, a check valve in the last-named passageway seating towards the second chamber, means providing a third fluid passageway between the reservoir and the first chamber, and a check valve in the last-named passageway seating towards the reservoir.

4. In a hydraulic lift truck, the combination of a chassis, a work-supporting platform, a spindle mounted transversely of the chassis, a sleeve rotatably mounted on the spindle, link means secured to the sleeve and to the platform whereby upon rotation of the sleeve the platform is moved about a radius relative to the chassis, a radial arm secured on the sleeve, a body having a pair of spaced parallel longitudinally slotted extensions pivotally secured to the arm, said body being movable longitudinally relative to the chassis, a pair of longitudinal, oppositely disposed, piston chambers in the body, a work piston secured to the base and slidably mounted in the first of the chambers, a pumping piston reciprocally mounted in the second chamber and having a rod disposed between said extensions, a cross pin extending through the rod and being slidable in said slots, an operating lever pivotally mounted on the base, link means operatively connecting the lever to the cross pin said body presenting a fluid reservoir, means providing a fluid passageway between the reservoir and the second chamber, a check valve in the passageway

seating towards the reservoir, means providing a second fluid passageway between the first and second chambers, a check valve in the last-named passageway seating towards the second chamber, means providing a third fluid passageway between the reservoir and the first chamber, a check valve in the last-named passageway seating towards the reservoir, and spring means nor-

6 mally urging the check valve in the second passageway into seated position, said spring means being unyieldable to pressure generated in the second chamber when the work-supporting platform is not burdened with a load to be lifted, and being yieldable to said pressure when said platform is burdened with a load to be lifted.

HERBERT E. PAGE.
